UNITED STATES PATENT OFFICE.

JAMES B. DAVIS, OF WASHINGTON, DISTRICT OF COLUMBIA.

LOCK FOR ORDNANCE.

SPECIFICATION forming part of Letters Patent No. 233,142, dated October 12, 1880.

Application filed August 16, 1880. (No model.)

To all whom it may concern:

Be it known that I, JAMES BAZIL DAVIS, a citizen of the United States, residing at Washington city, in the District of Columbia, have 5 invented new and useful Improvements in Apparatus for Discharging Ordnance, of which the following is a specification.

My invention relates to certain new and useful improvements in apparatus for discharging 10 ordnance.

In discharging ordnance the usual and almost universal method employed is to arrange a quill-primer within the vent. As the vent is left open at the time of the discharge of the 15 piece, flame and gases escape through the vent-passage, resulting in an enlargement of such passage, and the consequent cracking or starting of the powder-chamber at the point where the vent-passage enters, and in addition to 20 this result the cannoneer is compelled to use great care to avoid accident. It has been suggested, in order to overcome these disadvantages, to provide a vent-piece which is screwed into the breech of the gun, with a projecting 25 portion provided with a dovetail head, in which is formed a cavity for the reception of a fulminate-capsule, which is held in place by a swinging cover and exploded by a firing-pin or striker operated by a hammer. I have found that in 30 this last-named method it is exceedingly difficult to provide a perfect gas-check, and that unless such check is perfectly accomplished the copper cartridge or capsule is easily fused.

The object of my invention is to overcome 35 all the disadvantages incident to the construction of this above-named device; and it consists in the peculiar construction and arrangement of devices, hereinafter described, for the discharge of a steel or other metallic gas-check 40 primer of peculiar formation, and fully described in another application for Letters Patent which I have prepared and executed simultaneously with this.

In order that those skilled may fully understand my invention, I will describe the same, 45 referring by letters to the accompanying drawings, in which—

Figure 1 is a rear elevation of a breech-plug used in heavy ordnance with my improved devices secured thereto. Fig. 2 is a central ver-

tical section at the line *xx* of Fig. 1. Fig. 3 is a transverse section at the line *yy*, Fig. 1. Fig. 4 is a similar section at *zz* of Fig. 1; Fig. 5, a plan view of that portion of the face-plate immediately under the dotted line *zz*, Fig. 1; 55 and Fig. 6, a section at the line *11*, Fig. 1.

Similar letters indicate like parts in the several figures.

A represents the usual breech-plug employed to close the breech of ordinary breech-loading 60 heavy ordnance, and *B* is the handle by which it is turned to unlock it, ready to be withdrawn. *C* is a circular plate, which I secure in any suitable manner to rear face of the plug *A*. This plate is open centrally, as seen at *D*, into 65 the cavity *E* surrounding the projecting end of the vent-plug *F*, which is secured within the breech-plug *A*, and the rear end of the vent-plug *F* is formed with an annular groove, *G*, for the purpose presently to be explained. 70

H is a lever, pivoted at one end, at *I*, to the face-plate *C*, and extended at the other end and bent outwardly to form a handle, *J*. On the under side of this handle, projecting inwardly, is a partial cylinder, *K*, the lower end 75 of which is formed with a circular shoulder or rib, *L*, adapted to fit in the annular groove *G* of the vent-plug. This cylinder *K* is cut away at one side to allow it to pass the vent-plug *F* when the lever *H* is swung around upon its 80 pivot *I* to cover the vent and cause the rib *L* to occupy its place in the groove *G*.

M is a spring firing-pin, arranged in the lever *H* axially with the vent-passage.

N is an arm extending radially from the lever *H*, to provide a bearing at *O* for a swinging striker or hammer, *P*, which is operated by a lanyard, *Q*, passing around in a circular groove in the pivoted end of the hammer, as clearly shown in Fig. 2. The lower end of the 85 arm rests against the face-plate *C*, and is formed with a short tongue, *R*, adapted to travel under a hook, *S*, secured to the plate *C*, the object being to aid in holding the lever *H* against any backward movement, and in this 90 particular to assist the rib *L* on the part *K*, which, being centrally arranged, is the main reliance in this particular. As seen at Fig. 6, a spur on the under side of the pivoted end 95 of the lever *H* lies within a short cavity in 100

the face-plate, and limits the vibratory movement of the lever within the bounds necessary for its operation.

T is a hook secured to the under side of the lever, and adapted to travel under the head or flange of the cartridge U at the proper time to withdraw the same when the lever is swung rearward on a hinge-joint, V, provided close to the point I of its pivoted connection 10 with the face-plate.

It will be observed that the pivot I and hinge V permit two movements of the lever H, one parallel with and the other at right angles to the face-plate.

15 The handle portion J of the lever is bent outwardly at an angle of about thirty degrees, to avoid pinching the hand of the gunner between it and the breech-plug handle B.

W is a spring-bolt arranged in the face-plate and adapted to spring into a hole in the under side of the free end of the lever H and lock it against accidental movement after it has been brought into proper position for operating the firing mechanism.

20 X is a thumb-rod, which, on being pressed down, forces the spring-bolt back and releases the lever in an obvious manner when it is desired to vibrate the same on its pivot I.

In order to avoid the accidental operation 30 of the hammer P, I provide a spring-latch, a, the end of which is forced into a hole in the bearing end of the same, so as to lock the same in a closed position, rendering it necessary to pull out the latch before the hammer 35 can be operated by the lanyard.

The cartridge employed is such as I have described in the application for Letters Patent hereinbefore referred to, and it is arranged 40 within the vent-passage, so that one shoulder or flange of the cartridge rests upon the end of the vent-plug, the other flange being sufficiently far away from said end to permit the extracting-hook T to pass under the same.

From the peculiar construction of the cartridge U and its arrangement within the gun and with the firing mechanism, it will be observed that upon the explosion of the powder in the gun the forward end of the firing-cartridge expands to form a gas-check at that point, 50 and the firing-pin and central block or anvil of the cartridge, as described in the application herein referred to, prevent the escape of any gases at that point. The form of the lever H at each side of the central locking portion K is such that with the presence of the 55

cavity E the lever may be readily grasped to withdraw the plug A and direct it onto the usual supporting-tray, thus avoiding the use of the ordinary independent handles which are required for that purpose.

It will be understood that when guns are made having in view the employment of my improved firing mechanism the plate C may be dispensed with and the firing mechanism attached directly to the breech-plug.

What I claim as new, and desire to secure by Letters Patent, is—

1. In combination with the breech-plug A, adapted to receive a suitable priming-shell, the lever H, hinged at V, and pivoted at I to the breech-plug, and provided with suitable firing and locking mechanism, substantially as and for the purpose described.

2. The pivoted and hinged lever H, secured to the removable breech-plug and extended 75 backwardly each side of the center, and provided with a radial arm, N, at right angles thereto to receive the firing mechanism, whereby the lever may serve the purpose of a handle, substantially as described, for withdrawing the breech-plug.

3. In combination with the breech-plug A, formed with the cavity E and projecting vent-plug F, having annular groove G, the hinged and pivoted lever H, provided with the central and inwardly-projecting locking mechanism K L, and extractor T, substantially as and for the purpose set forth.

4. In combination with the swinging lever H and radial arm N, the hook T, arranged as 90 described, for extracting the cartridge, substantially as hereinbefore set forth.

5. The radial arm N, provided with the central locking mechanism, L, and circumferential locking-hook R, in combination with the 95 grooved vent-plug F and auxiliary locking-hook S, substantially as and for the purpose set forth.

6. The lever H, provided with locking and firing mechanism, as described, and extended 100 outwardly between the pivot and locking-point, to form a handle for the withdrawal of the breech-plug, as hereinbefore set forth.

In testimony whereof I have hereunto set my hand in the presence of two subscribing 105 witnesses.

JAMES B. DAVIS.
